PORTABLE ELECTRONIC CALCULATOR CASE

Gary E. Garnier, San Jose, Calif., assignor to National Semiconductor Corporation, Santa Clara, Calif.

Filed Feb. 21, 1975, Ser. No. 551,915

Term of patent 14 years

Int. Cl. D18—01

U.S. Cl. D26—5 C

Fig. 1

Fig. 2

Fig. 3

Fig. 4

Fig. 5

Fig. 6

FIG. 1 is a perspective view, taken from the left side and above, of a portable electronic calculator case showing my new design;

FIG. 2 is a top plan view thereof;

FIG. 3 is a side elevational view thereof;

FIG. 4 is a front elevational view thereof;

FIG. 5 is a rear elevational view thereof; and

FIG. 6 is a bottom plan view thereof.

I claim:

The ornamental design for a portable electronic calculator case, as shown and described.
